[57] CLAIM

The ornamental design for hand held welding gun, as shown and described.

DESCRIPTION

FIG. 1 is a prespective view of a hand-held welding gun showing our new design;

FIG. 2 is a front elevational view thereof;

FIG. 3 is a top plan view thereof;

FIG. 4 is a side elevational view thereof;

FIG. 5 is a rear elevational view thereof;

FIG. 6 is a bottom plan view thereof.

The broken line showing of the tool tip is for illustrative purposes only and forms no part of the claimed design.

FIG. 1

FIG. 2

FIG. 3

FIG. 4

FIG. 5

FIG. 6
